8 Claims. (Cl. 84—240)

1

This invention relates generally to piano actions and more particularly to an improved pivotal connection for joining the various members of a piano action.

In the design of piano actions, it is necessary to provide a plurality of relatively movable members which are arranged so that very fast and smooth operation can be provided. Further, it is desired that the moving parts be so constructed that no noise is produced by operation thereof. In the prior art, piano actions have been made largely of wood with the surfaces which contact each other being covered by felt or other resilient material which eliminates any noise. The various elements of the action have been connected together by pivots formed by metal pins which fit in felt bushings. Springs are required in some instances to restore the members to their normal position after having been operated. These actions have been objectionable in that the construction is inherently expensive and great care must be exercised in the adjustment thereof. The operation of such actions is greatly affected by moisture, and is not as fast as is desired.

In the copending patent application of Louis Messant, Serial No. 82,757, filed March 22, 1949, now Patent No. 2,571,155, there is disclosed and claimed a piano action in which the members are pivoted by knife edge connections with the members being held in assembled relation by members made of resilient material. This application is directed to improvements made in the piano action as disclosed in the Messant application.

It is an object of the present invention to provide an improved piano action in which the members are pivotally mounted for exceedingly fast operation.

A further object is to provide a piano action which is adaptable for construction from plastic and metal materials and which is not subject to changing characteristics due to different humidity conditions.

A feature of this invention is the provision of a piano action in which members are pivotally joined by knife edge connections so positioned that operation of the action causes the joined members to be held together with very little friction therebetween so that the action operates rapidly and works very easily.

Another feature of this invention is the provision of an action in which the pivoted members are of such construction that they can be formed from plastic or metal material, and in which the

2

pivoted members are held together by flat springs to permit easy assembly and disassembly thereof and to also compensate for wear of the members of the action.

5 Further objects and features, and the attending advantages of the invention will be apparent from a consideration of the following description taken in connection with the accompanying drawings in which:

10 Fig. 1 shows a piano action in accordance with the invention in the normal unoperated position;

Figs. 2 to 5 are cross sectional views along the indicated section lines of Fig. 1 illustrating the construction of various parts of the action;

15 Fig. 6 illustrates a modified action in accordance with the invention; and

Figs. 7 to 9 are cross sectional views along the indicated section lines of Fig. 6 further illustrating the construction of the modified form of the invention.

20 In practicing the invention there is provided a piano action in which the various members of the action such as the whippens, fly jack and mounting flanges are made of plastic or metal material. These various members are pivoted together for normal piano operation by joints formed by a sharp edge on one member and a V-groove in the associated member. Such pivotally connected members are held together by

25 resilient elements which cause the edges to bear against the associated grooves. The resilient elements may be made of metal, plastic or other suitable material. The pivotal connection may be provided by shaping one of the members so that it may extend through an opening in the other member with the resilient element being interposed between interlocking portions of the members. The associated edges and grooves are so positioned that movement of the members in

30 35 the normal operation of the action causes the edges to bear against the grooves so that the members will not tend to be forced open by the operation.

40 45 In Figs. 1 to 5 inclusive, there is illustrated one structural embodiment of the invention in which the pivotal connections in accordance with the invention are applied to the whippens, fly jack, hammer and damper. The whippens 60 are secured to the rail 51 by a flange 62 with the whippens 50 and flange being held together by a spring 63. The same spring 63 holds the jack 64 in assembled relation with respect to the whippens 60. The spring 63 is illustrated as a metal member but it is to be noted that any material having the desired resiliency characteristics may be used.

The whippen 60 has recesses therein to receive portions of the flange 62 and the jack 64. A channel is provided in the whippen having a surface 71 on which the spring 63 rests. A pin 72 is provided for holding the end of the spring adjacent the jack against the surface 71. The pivotal connection between the jack 64 and the whippen 60 is provided by the portions 65 on the sides of the jack having sharp edges which engage V-grooves 66 in the whippen. The jack also has a reduced portion with an edge 67, opposed to the edges 65, which engages the spring 63 so that the edges 65 are held in the grooves 66 by the spring.

The flange 62 extends all the way through the whippen 60 as illustrated in Figs. 1 and 5. The flange 62 has projections 68 on the sides thereof with sharp edges which rest in V-grooves 69 on the whippen. An opposed edge 70 on the flange 62 engages the spring 63. It will be noted that the pivotal connection between the whippen and the flange is such that as the whippen is raised by movement of the abstract 14, the pressure exerted will cause the V-groove 69 of the whippen to bear against the edges 68 so that the pivotal connection is forced more closely together. This causes no strain on the spring 63 so that the spring is required only for holding the members in position and not for bearing the force exerted therebetween. This relationship is also true of the engagement between the jack 64 and the whippen 60 as movement of the whippen will cause the grooves 66 to bear against the sharp edges 65 and will not flex the spring 63.

As stated above, the hammer 75 and the damper 76 are also connected to the rail 61 by knife edge pivotal connections. A single flange 77 cooperates with both the hammer 75 and the damper 76 to provide the connections. The flange 77 is secured to the rail 61 as by the screw 78 and includes recesses 79 and 80 for receiving portions of the hammer and damper respectively. The hammer has projections 81 on the sides thereof with sharp edges which bear in V-grooves 82 in the flange 77. The hammer also has an opposed centrally positioned edge 83 which engages the spring 84. This connection is shown more in detail in Fig. 4.

The connection of the damper 76 and the flange 77 is substantially the same as that of the hammer 75 and the flange. The damper includes projecting portions 85 on the sides thereof having sharp edges which engage grooves 86 in the flange. The damper also has an opening with an opposed edge 87 which bears against the spring 84.

In the operation of the action the abstract 14 is moved by key 13 and causes the whippen 60 to rotate in a counterclockwise direction so that the jack 64 bears against the knuckle 88 on the hammer 75 causing the hammer to rotate in a counterclockwise direction. This movement will cause the edges 81 on the hammer to bear sharply against the grooves 82 on the flange 77 so that the force produced is exerted directly between these members and does not cause the spring 84 to be flexed. The hammer is restored to the normal position by a spring 89 in the usual way.

As the whippen and jack move in a counterclockwise direction the projection 93 on the jack engages the let-off 94 so that the end of the jack is pulled away from the knuckle 88 and the hammer may move freely. A projection 95

is provided on the hammer 75 which engages the backcheck 96 secured to the whippen 60 to prevent undesired movement of the hammer after the head of the hammer strikes the string 91.

5 Movement of the whippen is transmitted through the spoon 90 to the lower end of the damper so that the damper is removed from engagement with the string 91. The damper is returned to position in engagement with the string by

10 spring 92.

Referring now to Figs. 6 to 9 inclusive, these figures show the use of metal flanges shaped to form one part of the knife edge pivotal connection. The action is of generally the same

15 configuration as in the preceding figures and includes a fixed rail 100, an abstract 101, whippen 102, jack 103, hammer 104 and damper 105. The whippen 102 is secured to the fixed rail 100 by the flange 106 which is shown more in detail

20 in Fig. 9. The flange is secured at one end to the rail 100 as by a screw 107 and the other end is positioned in an opening in the whippen 102. The latter end of the flange has projecting shoulder portions 108 which bear in V-grooves

25 109 on the sides of the whippen. An opening 110 is provided in this end of the flange having an edge 111 against which the spring 112 bears. A pivotal connection is thereby provided between the edges 108 and the grooves 109, with the

30 flange and whippen being held in assembled relation by engagement between the spring 112 and the edge 111 of the flange. The spring 112 is held on a surface 113 provided by a recess in the whippen 102 and is held in position on the surface

35 by a pin 114 in the same manner as described in connection with Fig. 1.

The jack 103 is pivotally connected to the whippen 102 by a metal flange or clip 115 which is secured to the jack as by screws 116 (Fig. 8). One end 40 of the flange includes shoulders 117 on either side of a reduced portion. The reduced portion extends in a recess in the whippen 102 and the shoulders 117 bear in grooves 118 in the portions on the sides of the recess. The flange has an opening 119 with a surface 120 which bears against the spring 112.

The hammer 104 and damper 105 are secured to the rail 100 by a single flange 121 which is secured to the fixed rail by a screw 122 (Figs. 5

5 and 7). The flange 121 extends at one end into a recess in the butt of the hammer 104. This end has a reduced portion and shoulders 123 at each side thereof which engage V-shaped grooves 124 in the sides of the hammer 104. The

55 reduced portion has an opening 125 therein with an edge 126 which engages the spring 127. The spring 127 is provided in a slot in the hammer butt and is held in position by a pin 128. The other end of the flange 121 also includes a reduced portion which extends in a recess in the

60 damper and shoulders 130 which bear against V-grooves 131 in the portions of the damper at the sides of the recess. This reduced portion includes an opening 132 having a surface 133 which engages a spring 134. The spring 134 is positioned in an opening in the damper 105 as is best shown in Fig. 6.

Both the hammer and damper may be held in their normal position by springs secured to 70 the flange 121 as shown in Figs. 6 and 7. The spring 135 returns the hammer to the position shown after it has been rotated counterclockwise into a position in engagement with the string. Similarly a spring 136 is provided for causing the damper 105 to engage the string

when the whippens are returned to the normal position as illustrated.

From the above, it is apparent that the pivotal connection in accordance with the invention provides a simple, inexpensive and highly desirable piano action. The various structures disclosed can be molded from plastic material or can be punched out of sheet metal. The cost of the molded plastic members and the punched out metal members will be a small fraction of that of typical wood actions having the usual pin and bushing joints. A further saving in cost results from the simplicity of assembly and the non-critical adjustment of the action. Actions constructed in accordance with the invention are very easy to operate and operate very fast, providing what is believed to be the fastest repeating action ever constructed. Maintenance of the action is reduced both because of the ease of assembly and disassembly thereof and because the spring members tend to compensate for wear of the parts so that substantial maintenance is not required. The construction of the pivotal connections so that the springs are not flexed during the usual operation of the parts results in long life of the springs.

While certain embodiments of the invention have been described which are illustrative thereof, it is obvious that various changes and modifications can be made therein without departing from the intended scope of the invention as defined in the appended claims.

I claim:

1. In a piano action, a flange secured to a fixed rail, a whippens and a fly jack, said flange and said fly jack being pivotally interconnected with said whippens and each including a reduced part with an aperture therein and portions with sharp edges projecting on the sides of said reduced part, said whippens having a pair of openings therein adapted to receive said reduced parts of said flange and said fly jack and portions on the sides of said openings having grooves therein for receiving said sharp edges, said sharp edges on said fly jack engaging said whippens on one side thereof and said sharp edges on said flange engaging said whippens on the side opposite to said one side, and a spring member engaging said whippens having ends extending in said apertures in said flange and said fly jack for holding said sharp edges in said grooves.

2. In a piano action, a flange secured to a fixed rail, a whippens and a fly jack, said flange and said fly jack being pivotally interconnected with said whippens and each including a reduced part with an aperture therein and portions with sharp edges projecting on the sides of said reduced part, said whippens having a pair of openings therein adapted to receive said reduced parts of said flange and said fly jack and portions on the sides of said openings having grooves therein for receiving said sharp edges, said sharp edges on said fly jack engaging said whippens on one side thereof, said flange extending through said whippens with the sharp edges thereof engaging said whippens on the side opposite to said one side, and a spring member engaging said whippens having ends extending in said apertures in said flange and said fly jack for holding said sharp edges in said grooves.

3. In a piano action, first and second members pivotally interconnected with a third member, said first and second members each including a reduced part with an aperture therein and portions with sharp edges extending on the sides

of said reduced part, said third member having a pair of openings therein adapted to receive said reduced parts of said first and second members and having portions on the sides of said openings with grooves therein for receiving said sharp edges, said sharp edges on said first member engaging said third member on one side thereof and said sharp edges on said second member engaging said third member on the side opposite to said one side, and a spring member engaging said third member having ends extending in said apertures in said first and second members for holding said sharp edges in said grooves.

4. In a piano action, a first fixed member, a second member pivotally interconnected with said first member, a third member pivotally interconnected to said second member, said first and third members each including a reduced part with an aperture therein and portions with sharp edges projecting on the sides of said reduced part, said second member having a pair of openings therein adapted to receive said reduced parts of said first and third members and portions on the sides of said openings having grooves therein for receiving said sharp edges, said sharp edges on said third member engaging said second member on one side thereof, said first member extending through said second member with said sharp edges thereof engaging said second member on the side thereof opposite to said one side, a resilient member engaging said second member having ends extending in said apertures in said first and third members for holding said sharp edges in said grooves, and means for moving said second member in a manner such that said sharp edges of said first member and said sharp edges of said third member are urged toward said grooves in said second member.

5. In a piano action, first and second members pivotally interconnected, said first member being fixed and said second member being movable during operation of said action, said first member including a reduced part with an aperture therein and a portion having a sharp edge on at least one side of said reduced part, said second member having an opening therein adapted to receive said reduced part of said first member and a groove on at least one side of said opening for receiving said sharp edge, and a spring member engaging said second member and extending in said aperture in said first member for holding said sharp edge in said groove, said sharp edge and said groove being so positioned that movement of said second member during operation of said action causes said groove of said second member to be urged toward said sharp edge of said first member.

6. In a piano action, a first member, a second member pivotally connected to said first member, said first member having an opening therein and grooves on the portions on each side of said opening, said second member being formed of sheet metal and including a reduced portion with projections having sharp edges extending therefrom, said reduced portion being positioned in said opening with said projections positioned in said grooves, said reduced portion having an aperture therein with a sharp edge oppositely disposed to and substantially aligned with said sharp edges of said projections, and a spring member engaging said first member and said sharp edge of said aperture for holding said first and second members in assembled relation.

7. In a piano action, a first member, a second

member pivotally connected to said first member, said first member being molded of plastic material and having an opening therein and grooves on the portions on each side of said opening, said second member being formed of sheet metal and including a reduced portion with projections having sharp edges extending therefrom, said reduced portion being positioned in said opening with said projections positioned in said grooves, said reduced portion having an aperture therein with a sharp edge oppositely disposed to and substantially aligned with said sharp edges of said projections, and a resilient flat metal member engaging said first member and said sharp edge of said aperture for holding said first and second members in assembled relation.

8. In a piano action, a first member, a second member pivotally connected to said first member, said first member being molded of plastic material and having an opening therein and grooves 20

5
10

on the portions on each side of said opening, said second member being formed of sheet metal and including a reduced portion with projections having sharp edges extending therefrom, said reduced portion being positioned in said opening with said projections positioned in said grooves, said reduced portion having an aperture therein with a sharp edge oppositely disposed to and substantially aligned with said sharp edges of said projections, and a spring member engaging said first member and said sharp edge of said aperture for holding said first and second members in assembled relation.
